UNITED STATES PATENT OFFICE

RICHARD F. MONTROY, OF DETROIT, MICHIGAN

DEVICE FOR REMOVING BROKEN ELECTRIC-LAMP BULBS

Application filed July 25, 1929. Serial No. 381,055.

This invention relates to devices for removing broken electric lamp bulbs which have become broken while screwed in their sockets, and the primary object of the invention is therefore to provide an improved tool for removing such bulbs in an expeditious manner.

Another very important object of this invention is to provide a device of the character above mentioned, which is simply constructed, strong, inexpensive, practical, positive and efficient in operation and further well adapted for the purpose designed.

Other objects and advantages of the invention will become apparent during the study of the following description taken in conjunction with the accompanying drawings, wherein:

Figure 1 is a side elevation of a tool constructed in accordance with this invention.

Figure 2 is a fragmentary detail view partly in section and partly in elevation illustrating the manner of appending the blades to the handle of the tool.

Figure 3 is a transverse horizontal sectional view taken substantially on line 3-3 of Figure 1 and looking in the direction of the arrows.

Figure 4 is a fragmentary side elevation of the lower end portion of the blades.

Figure 5 is a side elevation of a modified form of tool.

Figure 6 is a view similar to Figure 5 showing a further modification of the blade.

Figure 7 is a top plan view of the blade constructed in accordance with Figures 1 and 5.

Referring in detail to the drawings, and especially to Figures 1 to 4 inclusive, where 40 in it will be seen that I have constructed a tool for this purpose adapted to be secured to one end of an elongated rod or pole such as may be carried by electric light repair men so as to enable them to remove the bulb 45 without the necessity of a step ladder such as when the socket of the bulb is out of reach of the repair man as would be in the case where the electric light fixture is supported in a wall, ceiling or other supporting means 50 which would necessitate the use of a ladder.

In this connection then it will be seen that I have designated an elongated pole which may constitute the handle of my device by the reference character 5. At its upper end the pole 5 terminates in an elongated reduced extension or tongue 6.

In conjunction with a pole of this nature the invention comprehends the provision of an ejecting device designated generally by the reference character 7. As illustrated, the 60 ejector consists of a bulbous shaped body 8, said bulbous shaped body 8 merging at one end into a substantially elongated shank 9, which shank is bifurcated to provide spaced parallel extensions for attaching legs 10-10. 65

The attaching legs 10-10 of the shank 9 is adapted to receive therebetween the tongue 6 of the pole 5 and the tongue secured between the legs through the medium of bolts or other like fastening elements 11 70 passing through suitable aligned openings 12 formed in the respective legs and through the tongue 6 as clearly suggested in Figure 1.

At its opposite end the bulbous shaped body 8 of the ejecting device merges into a 75 tapered extension 13, which extension 13 at its reduced end terminates in a pointed prong 14. Extending laterally from opposite sides of the tapered extension 13 of the body and arranged in longitudinal alignment is a plurality of longitudinally spaced gripping fingers or blades 15. The blades 15 on one side are curved in one direction and have their free ends sharpened as at 16. Likewise the blades on the opposite side of the extension are curved in a direction opposite to that of the first mentioned blade and are likewise sharpened at their outer ends as at 16.

In using the device as just described, obviously when a bulb has become broken in a socket in order to remove the bulb, all the repair man need to do is to insert the ejector into the broken portion of the bulb so that the pointed extremity 14 of the extension will 95 penetrate that end of the bulb remaining in the socket where the fingers 15 will grip through the medium of their pointed ends the wall of the base portion of the broken bulb, whereupon by rotation of the pole 5 in a man- 100

ner similar in effect as a screw driver, the base portion of the broken bulb will be unscrewed from its socket, and hence removed in an efficient and expeditious manner.

In Figure 5, wherein is illustrated a modified form of my invention, it will be seen that the ejector 7 instead of the bifurcated shank 9 is projected with an elongated shank 9' which tapers towards its outer extremity and the shank 9' is adapted to be received in a correspondingly tapered socket 17 formed in the elongated tubular portion 18 of a suitable handle 19, said handle 19 at the opposite end of the tubular portion 18 terminating in a suitable hand grip 20.

This type of tool is adapted to be used when the socket containing the base portion of the broken electric lamp bulb is within easy reach of the repair man and would not necessitate the use of a step ladder or the like.

In Figure 6 I have shown another modified form of hand tool and as therein illustrated the invention comprehends the provision of a handle comprising an elongated tubular portion 21 constituting a shank for the handle, said tubular shank 21 at one end terminating in a hand grip 22 similar to the hand grip 20 of the hand tool as illustrated in Figure 5 and hereinbefore described.

In this instance the ejector comprises a shank portion 23 forming a continuation of the handle 21, and this shank 23 at its outer end tapers into an elongated penetrating prong 24. Gripping fingers 25 extend laterally from opposite sides of the shank 23, and these gripping fingers 25 are bent in a manner similar to the fingers 15 of the ejector as illustrated to advantage in Figure 7, wherein is shown the manner of construction of my preferred form of broken lamp bulb ejector.

In the form of my invention shown in Figure 6, it is to be noted that the blades 25 graduate in size, the smaller of the blades 25 being arranged inwardly from the outer end of the penetrating prong 24.

In using this form of my invention the outer end of the prong 24 will of course pierce the closed end portion of the seat of the base of the broken electric lamp bulb while the fingers 25 will grip the inner walls of the base so that by proper manipulation of the handle 20 the base of the broken electric lamp bulb will be unscrewed from its socket.

In view of the simplicity of my device, it is believed that from the foregoing description taken in connection with the accompanying drawings, a clear understanding of the operation, construction and advantages of a tool of this nature will be clearly understood and appreciated by those skilled in this art. A more detailed description thereof is deemed unnecessary.

It will be also seen that a tool of this na-

ture is strong, inexpensive, practical, positive and efficient and well adapted for the purpose designed.

Even though I have herein shown and described the preferred forms of my invention, it is to be understood that the same is susceptible to changes fully comprehended by the spirit of the invention and the scope of the appended claims.

Having thus described my invention, what I wish to claim is:

1. In a tool for ejecting broken electric lamp bulbs from their sockets, in combination with a handle, of a body member adapted to be injected into the base portion of the broken bulb, said body portion being provided at one end with a penetrating prong for piercing the base of the broken electric lamp bulb, said body portion having oppositely curved gripping fingers extending laterally therefrom for engagement with the base of the broken electric lamp bulb as and for the purpose specified.

2. In a tool of the class described, a shank terminating at one end in a piercing prong, and oppositely curved gripping fingers extending laterally from said shank at said one end, and a handle member carried by said shank at the opposite end of said shank.

3. A tool of the class described comprising in combination a shank having an integral piercing tongue, and oppositely curved gripping fingers extending transversely of said shank.

In testimony whereof I affix my signature.

RICHARD F. MONTROY.
